UNITED STATES PATENT OFFICE.

ALFRED G. CRIPPS, OF INDIANAPOLIS, INDIANA.

SECTIONAL HEATING BOILER.

Application filed June 25, 1923. Serial No. 647,571.

To all whom it may concern:

Be it known that I, ALFRED G. CRIPPS, residing in the city of Indianapolis, in the county of Marion and State of Indiana, a 5 citizen of the United States, have invented a new and useful Improvement in Sectional Heating Boilers, of which the following is a full, clear, and exact specification, reference being had to the accompanying drawings, 10 which form a part thereof.

My invention relates to sectional heating boilers, and more particularly to sectional heating boilers adapted to burn soft or bituminous coal and to consume most of the 15 smoke and gases which ordinarily pass through the breeching and up the chimney thereby causing great waste of coal.

Heretofore devices have been attached to boilers and have been incorporated therein 20 in an attempt to avoid this waste and to burn the gases of combustion which contain a high per cent of the heat units of the coal fed into the combustion chamber and which ordinarily pass up the chimney unburned. 25 However, those devices which did burn even a small per cent of the gases required such a high degree of skill in stoking as to preclude their common use. Even when stoked with care and skill the combustion chambers 30 of boilers using these devices contained live coals for only a part of the length of the grate therein, and the rest of the grate was covered with dead coals or ashes. Hence it can be seen that no matter whether boilers 35 having these said devices incorporated therein were stoked expertly or not they were either ineffectual in properly burning the gases of combustion or were inefficient or were both ineffectual and inefficient.

40 The objects of my invention are to provide a sectional heating boiler in which low grades of coal will be completely burned without smoke; to provide a sectional heating boiler in which the gases of combustion are burned, thereby utilizing the heat units 45 therein which are ordinarily wasted; and to provide a sectional heating boiler having horizontal flues extending longitudinally thereof and having vertical flues extending 50 downwardly from said horizontal flues and being connected at their lower ends with an air passage extending longitudinally of said boiler and arranged with inlet openings 55 from the combustion chamber thereof, where- by the gases of combustion are mixed with air and are completely burned.

My invention is fully shown in the accompanying drawings wherein similar letters are used to designate similar parts. Fig. 1 is a rear view of the front section of the 60 boiler; Fig. 2 shows an intermediate section of the boiler; Fig. 3 is a front view of the back section of the boiler; Fig. 4 is a cross section of my improved sectional boiler along the lines 4—4 of Figs. 1, 2 and 3; and Fig. 5 is a cross section of my improved 65 sectional boiler along the lines 5—5 of Figs. 1, 2 and 3.

Referring to the figures, the sectional 70 boiler comprises the front section A, the intermediate sections B and the back section C. Each intermediate section comprises a body portion having, extending lengthwise therethrough, two side flues J and two intermediate flues J'. Each section is also 75 provided with two depending water legs D, one on each side of the section, which extend downwardly from the body portion. Each section has an overhanging water filled 80 portion G which projects downwardly from the lower surface of the upper body portion and which extends between the water legs so as to connect them. This overhanging portion G is of less thickness or dimension 85 in the direction of the length of the boiler than the body portion or the water legs. Each of the intermediate sections has formed on each side of each water leg a channel 90 whose upper end opens into the side flue J and whose lower end opens into the combustion chamber M between the water legs. When the sections are assembled to form a 95 boiler the channels formed in the faces of the water legs D form vertical flues H which extend upwardly from the combustion chamber M to the horizontally extending flue J.

The front section A and the back section 100 C are provided with water spaces E and F as shown in Fig. 4. The sections are connected to one another near the top of the body portion by means of nipples which are placed in the opening a' provided therefor and the sections are also connected to one another by nipples placed in the openings a provided at the lower ends of the 105 water legs D. The horizontal flues formed by the flue openings J' extend from front to rear of the boiler and discharge into the breeching L arranged on the back section C as shown in Fig. 5. Circulation of the gases 110 from the side flues J to the intermediate flues J' takes place through large flue open-

ings provided in the front section as shown in Fig. 1 and which are closed by the doors K as shown in Fig. 5. At the bottom of the combustion chamber M there is placed 5 the usual grate N with the ash pit O beneath it. Each intermediate section is provided on each side thereof with an elongated air passage arranged vertically and preferably just inside of the water legs D. 10 Each of these air passages is provided with suitable enclosing walls comprising an inner wall provided with a notch on each side of the water leg close to the crown sheet m and the walls of each of the air passages 15 at the lower end thereof are also provided with similar notches. When the sections are assembled to form a boiler the upper notches in adjacent sections register so as to form the openings Q between the air passages P and the combustion chamber near 20 the top thereof, and the notches in adjacent sections near the bottom of the passages P register to form the openings R between said air passages P and the combustion chamber M and the vertical flues H as 25 shown in Figs. 1, 2 and 3. The air passages P preferably extend from substantially the crown plate m or the top of the combustion chamber M to a point below the median line 30 thereof.

The circulation of the gases through the boiler is substantially as follows: Some of the gases of combustion pass from the combustion chamber M directly upward through 35 the vertical flues H, but for the most part the extremely hot gases of combustion are gathered in the upper part of the combustion chamber in the pockets formed between the overhanging portions G and escape 40 therefrom through the openings Q into the air passages P. Here the hot gases are mixed with air which enters through intakes S which are preferably arranged at the front end of the boiler and maintained 45 constantly open. The mixture of the gases and air then passes from the air passages P through the openings R into the vertical flues H, and from there into the outside 50 horizontal flues J. The gases pass forwardly through the flues J to the front end of the boiler where they enter the intermediate flues J' through which they pass to the breeching L and from there they pass to the chimney, all as indicated by the arrows in 55 Fig. 5.

The vertical flues H formed by the channels cast on each face of the vertical legs D are clearly shown in Figs. 4 and 5, and the air passages extending from front to 60 rear of the boiler, between the combustion chamber and the water legs D are shown in Fig. 4. The thickness of the overhanging portions G as compared to the thickness of the intermediate sections is shown in Fig. 4. 65 The openings Q and R whereby communica-

cation is afforded between the air passages P and the combustion chamber and the vertical flues H are also shown in Fig. 4.

Since, as herebefore stated, the mixture of air and gases from the air passages P 70 passes through the openings R above the point where the vertical flues H enter the combustion chamber M, some part of the mixture may find its way into the combustion chamber M but, for the most part, all 75 of the mixture will be drawn up the vertical flues where it is burned by the flames and extremely hot air which enters the flues from the combustion chamber. This burning may continue during the passage up the flues H and into the horizontal flues J and J'. The mixture of air and gases in the air passages P is at a very high temperature 80 since the gas enters the passage through the inlet openings Q directly from the combustion chamber and because of this the mixture is more quickly and completely burned when it passes into the flues H. It can be readily seen that virtually all the heat units in the 85 coal fed into the combustion chamber are utilized to make steam since the gases of combustion, which ordinarily pass incompletely burned from the combustion chamber up the chimney, will in my improved sectional boiler be mixed with oxygen and 90 returned to the side flues H to be burned.

It is not my intention to limit my invention to the exact details of construction shown in the drawings since my invention 100 may be adapted to various different types of boilers with equal utility.

What I claim as new and desire to secure by Letters Patent, is:

1. A cast iron sectional boiler comprising 105 a plurality of intermediate sections each having a body portion with a depending water leg on each side thereof, said body portion having flue openings therethrough, each of said legs having a channel formed in the rear and front face thereof which channels terminate in a flue opening at their upper ends and in the space between said legs at their lower ends, each of said sections having an overhanging portion of less thickness than said section adapted to contain 110 water and extending between said water legs, each of said water legs being provided with an air passage on the inner side thereof, and each air passage having an inner wall with a notch arranged in the upper end thereof on each side of said overhanging portion and each air passage having an opening arranged at the lower end thereof on each face of said section so as to connect said air passage with said channels. 115

2. A cast iron sectional boiler comprising 120 a plurality of intermediate sections each having a body portion with a depending water leg on each side thereof, said body

portion having flue openings therethrough, each of said sections having an overhanging portion of less thickness than said section adapted to contain water and extending between said water legs, each of said water legs being provided with an air passage on the inner side thereof, and each air passage having an inner wall with a notch arranged in the upper end thereof on each side of said overhanging portion and said inner wall also having a notch arranged at the lower end thereof on each face of said section.

3. A sectional cast iron boiler comprising end and intermediate sections joined to form an upper body portion and two depending portions arranged one on each side of said body portion to form a combustion chamber therebetween, said body portion having side and intermediate longitudinal flues therein, and said depending portions having vertical flues connecting said side flues with the lower part of said combustion chamber, a wall extending from front to rear on each side of said combustion chamber parallel to said depending portions and connected therewith to form an air passage, said wall having openings therethrough near its upper end to connect the upper part of said combustion chamber with said air passage and having also openings therethrough near its lower end whereby said air passage is connected with said vertical flues.

4. A sectional cast iron boiler comprising end and intermediate sections joined to form an upper body portion and two depending portions arranged one on each side of said body portion to form a combustion chamber therebetween, said body portion having side and intermediate longitudinal flues therein, said boiler having an air passage extending longitudinally thereof on each side of said combustion chamber, and said air passage having inlet openings leading from said combustion chamber near the top thereof and having also outlet openings below the median line of said combustion chamber.

5. A sectional heating boiler comprising joined end and intermediate sections and having a combustion chamber therein, horizontal flues extending longitudinally above the crown plate of said combustion cham-

ber, a plurality of vertical flues extending downwardly from one of said horizontal flues and terminating in said combustion chamber, and water legs between adjacent vertical flues, said sectional boiler having an air passage with one end thereof open to the atmosphere and arranged longitudinally of said boiler between said combustion chamber and said vertical flues and provided with inlet openings from said combustion chamber near the top thereof and with outlet openings into said vertical flues near where said vertical flues connect with said combustion chamber.

6. A sectional heating boiler comprising joined end and intermediate sections and having a combustion chamber therein, horizontal flues extending longitudinally above the crown plate of said combustion chamber, a plurality of vertical flues extending downwardly from one of said horizontal flues and terminating in said combustion chamber, and water legs between adjacent vertical flues, said boiler having an air passage having inlet openings leading from said combustion chamber near the top thereof and having also outlet openings into one of said vertical flues below the median line of said combustion chamber.

7. A sectional heating boiler comprising joined end and intermediate sections and having a combustion chamber therein, horizontal side and intermediate flues extending longitudinally of said boiler above said combustion chamber, vertical flues extending downwardly from said side flues on each side of said combustion chamber and connecting therewith, water spaces between adjacent vertical flues, overhanging water filled portions extending across the top of said combustion chamber between said water spaces at the sides of said combustion chamber so as to form transverse pockets therein between adjacent overhanging portions, said boiler having an air passage extending horizontally along each side of said combustion chamber, and said air passage having inlet openings from said transverse pockets and having outlet openings into said vertical flues.

In witness whereof I have signed my name to this specification.

ALFRED G. CRIPPS.
